LIQUID COATING DEVICES

Raymond H. Parker, 55 Warren Ave., Plymouth, Mass.
Filed Aug. 25, 1961, Ser. No. 134,026
3 Claims. (Cl. 118—252)

The present invention relates in general to liquid coating devices, and especially to devices for applying a film of liquid adhesive to sheets or strips of thin and flexible material such as paper labels or the like, or to larger sheets of material such as are used in covering books. These devices are herein termed label pasters for present purposes.

The invention is more particularly an improvement in the label paster of my previous Patent No. 2,573,052, granted Oct. 31, 1951, and has the object of simplifying the construction and use of such prior device. Thus, the present invention aims to provide a flat feed table to support and guide the labels or other sheets into proper contact with the adhesive-applying roller, to obviate the need for precise shaping of my previous concave feed table to match the concave profile of the roller. It further aims to provide simplified and more accurately controlled adjustment of the scraper or stripper used to remove the excess quantity of adhesive normally picked up by the roller and leave the desired thickness of the film of adhesive on the roller, so as to suit the consistency of the particular adhesive employed. Another object is to provide a guide of simplified form for holding down the label or strip against the roller, and one which will give more perfect contact of the label against the roller and hence more complete coverage of the label through transfer of the adhesive from the roller's surface to the label, and to provide simpler and easier adjustment of such guide for different thicknesses, stiffness, or consistencies of the paper or other material composing the label.

To make possible the use of a flat feed table, corresponding improvements are made in the label guiding means and the adhesive-stripping devices for the applying roller.

To attain greater ease of adjustment of the positions of the guide and of the scraper, preferably these two adjustments are correlated so that they are made by one setting which for simplicity is done by mounting them fixedly on the flat feed table and arranging the feed table so that it may be tilted about an axis so placed as to set the guide and scraper closer to or further from the surface of the roller as the particular stock and adhesive used may require. While the adjustment of the guide which directs the label or sheet against the roller is relatively not critical, the adjustment of the scraper is considerably more so, as it is necessary to maintain it in substantially parallel relation to the concave surface of the roller throughout the entire length of the latter. Such uniform spacing, or constant width of the gap throughout the length of the roller, is needed both to apply a film of adhesive of the right thickness and uniformity to the label, and also to prevent the adhesive from accumulating and building up a thick coating on the end portions of the roller's surface which lie outside the paths of the margins of the labels as fed through the device and which hence are not stripped down by the transfer of the adhesive to the successive labels. If the glue or paste is thus allowed to increase the effective diameter of the end-portions of the roller, it interferes with the feed of the labels by building up till it leaves insufficient space for the labels to pass if they are occasionally fed a bit off-center by the user, resulting in jamming, and by wiping off onto the guide itself where it causes the labels to stick to the guide, also with resultant jamming, and to be transferred to the face of the label and smeared thereover in applying the label.

2

The novel adjustment of the scraper setting by pivoting the feed table overcomes the difficulty otherwise inherent in using a sliding adjustment of the scraper, namely that the glue or paste sets up on and in the guideways or other supporting surfaces which such method requires, and makes the adjustment difficult or troublesome. Since the whole range of adjustment needed for the gap is normally about $\frac{1}{16}$ inch, the pivotal mounting of the feed table about a horizontal axis near the roller makes easy a fine adjustment of the spacing of the scraper, such as would be measured in hundredths of an inch, by a much simplified movement of the remote end of the feed table. It permits this tilting of the table to be effected in predetermined and indicated amounts, through lifting and lowering such end by a movable wedge, herein a cam whose angular displacement is shown by an index moving over a scale fixed on the reservoir or tank for the adhesive, or other part.

Other objects of the invention, and the manner of their attainment, are as set forth hereinafter.

An illustrative embodiment of the invention is shown in the accompanying drawings, in which

FIG. 1 is a plan view of the label paster, showing the driving means for the roller.

FIG. 2 is a side elevation of the device, partly in section, the driving motor being omitted.

FIG. 3 is a vertical section on line 3—3 of FIG. 1.

FIG. 4 is a vertical section on line 4—4 of FIG. 1.

The improved liquid coating device comprises a rectangular tank 1 to hold the liquid adhesive, open at the top and having a bottom 2 of inverted V-shape with the ridge 5 at the apex of the V extending longitudinally of the tank, the tank preferably being of plastic material either assembled from sheet stock or molded in one piece, 35 as desired.

The adhesive-applying roller 7 is mounted to dip into the adhesive in the tank, being supported by means of its integral web 9, located at mid-length, upon a shaft 11 freely rotatable in bushings 13 fixed in the side walls of the tank, the shaft being held from endwise movement by a collar 15 fixed on one end by a set screw, and by a cotter pin 17 put through the shaft and bearing against the flanged end of the adjacent bushing 13. The roller 7 is positioned on shaft 11 with its ends equidistant from 45 the respective side walls of the tank by spacers 19 whose flanged inward ends 21 abut against the web 9, against which they are held by nuts 23 threaded on the enlarged diameter portion of shaft 11 and bearing against the outer ends of the spacers 19.

50 The roller 7 has its outer or working surface in the shape of a concave spindle whose profile is defined by two right conic frusta disposed with their small ends opposed and joined, the profile of each cone being slightly concave, as shown in FIGS. 1 and 4. The roller is integral, and is made hollow for purposes of lightness and economy, and also for its action in mixing the adhesive, which flows in and out of the ends of the cone during its rotation.

55 Driving means for rotating the roller 7 continuously during use is provided by a small electric motor 25 supplied with current via leads 27 and equipped with reduction gearing 29 whose power output shaft 31 is detachably connected to the shaft 11 of the roller by tongue-and-slot joint 33, thereby rotating the roller at reduced speed.

60 The feed table 35 is a flat sheet, with its plane top surface parallel to the roller's axis, and conveniently made of transparent plastic enabling the adhesive level to be checked visually. It is provided with two wings 37 affixed to the lateral edges of the feed table and extending downwardly in close contact with the outside walls of the tank and pivoted at their lower extremities on studs 39 which are fixed in the ends of the arms and rotatable in sockets

41 formed in and extending only partway through the side walls of the tank 1.

The end of the feed table 35 is made to serve as the scraper or stripper which determines the wanted thickness of the film of adhesive picked up by the roller as it rotates counter-clockwise, FIG. 3, with its lower portion immersed in the liquid adhesive 40 to a depth sufficient to wet its entire length. For this purpose, the end of the table 35 adjacent the roller is beveled to a chisel edge 43 and given a contour in plan view which matches precisely the contour of the roller 7 where the latter would be intersected by a prolongation of the plane of the bottom surface of feed table 35 when the latter occupies its most generally used position. Thus matched, the edge 43 of the scraper can be disposed in precisely parallel relation to the portion of the roller nearest thereto, throughout the entire common length of the roller and of this edge, so as to scrape back the excess thickness of the adhesive 41 and leave a coating of uniform thickness on the roller for transfer to the label being pasted.

Since different consistencies of adhesive and different thicknesses of the coating thereof applied to the material being treated are needed for various purposes, as noted, provision is required for changing the width of the gap between the scraping edge 43 and the roller, and thus controlling and limiting the depth of adhesive allowed to remain on the roller by edge 43 for application to the label as the latter is fed flatwise by hand pressure over the top surface of table 35 and the roller. This adjustment is accomplished simply in the present device by a cam device in the form of a metallic rod 47 of initially round section which extends at right angles across the tank beneath the feed table 35 and rotates in half-bearings cut in the top edge of the tank for its reception. Throughout the full width of the feed table this rod is reduced to half-round section as shown at 49, the thus flattened portion being uppermost and engaging with the under surface of the feed table 35. Both ends 51 of rod 47 are bent downward into parallel and frictionally gripping relation with the respective side walls of the tank 1, so as to retain the rod in any angular position about its main axis which may be given to it. As is obvious, angular movement of the ends 51 counter-clockwise, FIG. 3, about such axis causes the righthand edge of the half-round portion 49 to cam the feed table upward with attendant rotation 45 of the table about its pivots 39.

Such tilting of the feed table swings its scraping edge 43 into closer proximity to the surface of roller 7. The higher the end of the feed table is lifted by the cam 49, the narrower the gap becomes, and the thinner the coating of adhesive left on the surface of the roller for transfer to the label by the scraper 43.

Index numbers may be inscribed on the side walls of the tank along the arc of swing of the ends 51 of the cam, for easy reestablishment of the setting of the gap found to be best adapted for a given combination of label and adhesive.

In practically all normal use of the device, the width of the gap between the scraping edge 43 and the confronting surface of the roller 7 will not exceed $\frac{1}{16}$ of an inch, but the reduction of this gap needed to work with different consistencies of paper and adhesive would be measured in thousandths of an inch. This micrometric scale of adjustment is attained by putting the cam 49 at a location substantially twice as far from the pivots 39 as the scraping edge 43 is located. Thus, shifting the angular position of the ends 51 of the cam produces a small change in the elevation of the right-hand end of the feed table which effects a much smaller change in the elevation of the scraping edge 43 and in its spaced relation to the roller's surface.

The contour of the scraping edge 43 is V-shaped, as needed to match the shape of the roller's surface at the location where the feed table's bottom plane intersects it, and hence the salient 61 of edge 43, the apex of the V,

opposite the waist of the roller, is on a longer radius from the axis through pivots 39 than are the two ends of edge 43. Thus it is not geometrically possible to maintain the two surfaces truly parallel and the gap precisely equal throughout the full range of adjustment. But by locating the axis through pivots 39 vertically below the rims of the maximum diameter of the roller, i.e., on the vertical line tangent to the rising side of the roller's end, and at the level of the bottom of the rims, and giving the salient a radius about this axis such that its arc of swing if continued would pass just below the axis of the roller 7, a satisfactory approximation is attained. In narrowing the gap, the end-portions of edge 43 approach the surface of roller 7 slightly closer than the mid-portions at and about the salient 61, with the advantage that with close settings of the gap the unused adhesive on the outer ends of the roller not overlapped by the centrally-fed label is kept from accumulating thereon.

As in my prior patent, the adhesive-applying roller 7 is given its concave shape in order to bend up the lateral margins of the label so as to form a trough or valley in the label extending longitudinally thereof, namely in the direction of its movement, to stiffen the sheet against transverse bending and thus render it impossible or substantially so for the label to adhere to and follow around the periphery of the roller over and in contact with which it is traveling while receiving the coating of adhesive.

To force the label into contact with the profile of roller 7 throughout the entire width of the label, so as both to insure the coating of the whole underside of the label and also to make it take and hold the desired trough shape which compels it to leave the roller at a tangent, a guide 63 of flat stock, preferably the same transparent material as feed table 35, is mounted in parallel and spaced relation on the feed table 35 over the scraper 43 and adjacent portions of the table. The spacing of the guide from the table is close, of the order of $\frac{1}{16}$ inch, established by spacers 65 cemented between and to these two members at the two ends of the guide. The lower edge of the left-hand or delivery end 67 of guide 63 is given a shape in profile matching the contour of roller 7 where the latter is intersected by the extension of the plane of the guide's under surface, after the manner described in regard to the scraping edge 43. The edge of the guide, however, has considerably more clearance from the roller than the scraper. The right-hand edge of guide 63 is V-shaped in plan, and undercut as indicated at 69 to guide the label easily beneath it as the label is slid forward by hand along the table and onto the roll. The apex 71 of the V, being below the low point at the waist of the roller, insures that even the portion of the label traveling over the waist is brought into wiping contact with the roller and its coating of adhesive. This apex and the rest of the guide's edge force the label into conformity with the profile of the roller and insure the maintenance of the trough formed therein and the resultant tangential projection of the label beyond the roller where it may be easily grasped for removal and application.

The V-bottom 2 provided in the rectangular tank 1 reduces the quantity of adhesive needed to keep it up to the proper working level on the roller 7. A cover 75, FIG. 2, fitting closely upon the rim of the tank around the roller 7 and recessed to mount upon the feed table, and equipped with lugs 77 to hold it in place, is provided to keep the fluids in the adhesive from evaporating while the paster is not in use.

The device is also useful for applying water to the surface of a dry coating of adhesive already in place upon such sheet for the purpose of activating the adhesive.

The motor 25 is fixedly mounted upon a rectangular base 81, conveniently made of plastic sheet material. This base has fixed thereon two triangular fins 83, FIG. 4, having their upper edges shaped to fit precisely within the inverted V-bottom 2 of the tank, and are spaced apart to engage simultaneously the inward surfaces of the end walls

of the tank, as shown in FIG. 3. Thus the tank is held in fixed operative position upon the base 81 with the slotted end 33 of the roller shaft 11 in driving engagement with the output shaft 31 of the motor. Yet the entire device can be instantly lifted off from its base and disconnected from the output shaft, for removal for cleaning or other purposes.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but what I do claim is:

1. A label paster having in combination a reservoir for liquid adhesive, a roller of concave profile rotatably mounted therein so as to dip into the adhesive, means for rotating the roller, a feed table having a flat label-supporting surface disposed in a plane parallel to the roller's axis and intersecting the roller and an edge adjacent the roller matching in contour the shape of the proximate surface portion of the roller, means mounting the table for pivotal movement carrying the edge into adhesive-stripping relation to the roller, and a guide above and in fixed spaced and parallel relation to the surface of the feed table, adapted to engage the upper surface of a label being slid over the table and roller and force the label into conforming contact with the concave surface of the roller.

2. A label paster having in combination a reservoir for liquid adhesive, a roller of concave profile rotatably mounted therein so as to dip into the adhesive, means for rotating the roller, a tilting feed table having a flat label-supporting surface and an adhesive-stripping edge fixed thereon in proximity to the roller's surface, a label guide fixed on and extending beyond the end of the table having an edge in spaced and parallel relation to the label-support-

ing surface adapted to force a label slid along such surface into conformity with the profile of the roller, and cam means to effect the tilting of the table and thereby determine the spaced relation of the guide and the adhesive-stripping edge with respect to the roller's surface.

3. A label paster having in combination a reservoir for liquid adhesive, a roller of concave profile rotatably mounted therein so as to dip into the adhesive, means for rotating the roller, a feed table tiltably mounted on the reservoir and having a flat label-supporting surface disposed in a plane parallel to the roller's axis and intersecting the roller, and having a convex edge adjacent the roller matching in contour the shape of the proximate surface portion of the roller, means in connection with the feed table for limiting the thickness of adhesive carried by the roller comprising a scraper positioned in a spaced relation from the surface of the roller that is determined by the degree of tilt of the feed table, and a guide above and in fixed spaced and parallel relation to the surface of the feed table adapted to engage the upper surface of a label being slid over the table and roller and force the label into conforming contact with the concave surface of the roller.
